(57) **CLAIM**

The ornamental design for an orthodontic appliance forming assembly, as shown and described.

DESCRIPTION

FIG. 1 is an enlarged top perspective view of an orthodontic appliance forming assembly;

FIG. 2 is an enlarged bottom perspective view of the forming assembly of FIG. 1;

FIG. 3 is a top plan view of the forming assembly of FIG. 1;

FIG. 4 is a left side view of the forming assembly of FIG. 1;

FIG. 5 is a right side view of the forming assembly of FIG. 1;

FIG. 6 is a front view of the forming assembly of FIG. 1; FIG. 7 is a rear view of the forming assembly of FIG. 1; FIG. 8 is a bottom plan view of the forming assembly of FIG. 1; and,

FIG. 9 is a perspective assembly view of the forming assembly of FIG. 1 having an orthodontic appliance mold positioned thereon and a thermoplastic sheet material positioned over the forming assembly.

The broken lines shown in the drawings are included for the purpose of illustrating portions and environmental elements of the orthodontic appliance forming assembly and form no part of the claimed design.
